UNITED STATES PATENT OFFICE.

JULIUS DUNNER, OF NEW YORK, N. Y.

SECTIONAL HAIR COMB.

Application filed August 23, 1921. Serial No. 494,719.

To all whom it may concern:

Be it known that I, JULIUS DUNNER, a citizen of Russia (first paper taken out), and resident of New York, in the county of 5 New York and State of New York, have invented certain new and useful Sectional Hair Combs, of which the following is a specification.

This invention relates to new and useful 10 improvements in sectional hair-combs, and the principal object of the same is the provision of a sanitary hair-comb having parts made and assembled in such a manner that the teeth may be entirely removed for 15 thorough cleaning, and that if any of the teeth become damaged or broken, new teeth may be readily installed.

Another object of the invention is the provision of a construction involving features 20 of the character specified, which may be employed in providing combs equipped with teeth pointed for use on both extremities, or at one extremity only.

A still further object of the invention is 25 the provision of a tooth holding device for use in conjunction with a comb of the construction above stated.

With the foregoing objects in view and others, the invention resides in the details of 30 construction and in the arrangement and combination of parts hereinafter described, defined in the claims, and illustrated in the accompanying drawings, in which:—

Figure 1 is a side elevation of a comb 35 made in accordance with this invention, but with some of the teeth omitted.

Figure 2 is a side elevation of one of the teeth separately.

Figure 3 is a cross section on the line 40 A—A of Figure 6.

Figure 4 is a cross section on the line B—B of Figure 5.

Figure 5 is a side elevation of the tooth locking member and its end piece separately.

Figure 6 is a side view of the tooth supporting strip and its end piece separately.

Figures 7 to 12 inclusive are similar views to Figures 1 to 6 inclusive illustrating a comb constructed according to this invention having teeth with the necessary service or combing points at but one end thereof.

Figures 13 to 18 inclusive are similar views to Figures 1 to 6 inclusive illustrating a modification, and Figure 19 is a horizontal 55 section taken on the line C—C of Figure 17.

Figures 20 to 26 inclusive are similar views

to Figures 13 to 19 inclusive illustrating a comb similar to that shown in the last mentioned figures, but having teeth with the necessary service or combing points at but 60 one end thereof.

Figures 27, 28 and 29 illustrate a device for holding teeth when they are removed from a comb constructed according to this 65 invention.

Referring to Figures 1 to 6 inclusive of the drawings, 1 indicates a tooth holding strip approximately rectangular in plan made of any suitable metal or material, such as celluloid, and 2 indicates an end piece 70 fixed thereto, the latter being provided with a slot 3 adapted to receive the co-operating end of the holding strip 1 which may be gummed or otherwise secured therein. The end piece 2 is also provided at one side thereof with a semi-circular flange 4 which is bored and screw threaded to receive and retain the correspondingly screw-threaded end 5 of a tooth locking member 6 which is also provided with an end piece 7 in which there 75 is formed a groove 8 to receive the other end of the holding strip 1. This end piece 7 is also formed with a semi-circular flange 9 bored but not screw-threaded adapted to receive the locking member 6 in such a manner as will permit its revolution by a small 80 wheel 10 fixed on the end thereof.

The tooth holding strip 1 is rectangular in cross section with the exception that on one face is provided a semi-circular recess or 90 depression 11 running longitudinally thereof.

Each tooth 12 is of the shape shown in Figure 2, that is to say, it is provided with bevelled or curved extremities 13 in order 95 to provide the necessary service points, whilst it is provided with a rectangular slot 14 to enable it to pass on to and be held by the holding strip 1.

At one side thereof each tooth is also 100 formed with a semi-circular projection 15 which is bored to provide a semi-circular recess 16 of the same diameter as the depression 11 in the holding strip 1. Thus, after the required number of teeth 12 have been 105 threaded on to the holding strip, the complementary recesses 16 in the teeth 12 and the depression 11 in the strip 1 form a circular passageway extending longitudinally of the comb into which can be inserted the locking 110 member 6, the screw-threaded end 5 of which is adapted to screw into the screwed bore of

the semi-circular flange 4 of the end piece 2, as shown in Figure 1, and thus the teeth 12 will be locked on the holding strip 1 between the end pieces 2 and 7, when the comb 5 is ready for use.

The end pieces 2 and 7 extend beyond the sides of the retaining strip 1 and preferably to a distance equal to that of the combing points of the teeth 12, and they more or less 10 form end teeth as will readily be seen in the drawings.

One of the flat sides or faces of each tooth 12 is provided with a shoulder piece 17 and these shoulders act to space the teeth as will 15 be evident from Figure 1. The end piece 7 is also preferably provided with a shoulder 18 adapted to space that tooth abutting thereagainst when the comb is assembled.

In order that the teeth 12 shall always be 20 placed on the strip 1 in the correct manner, the rectangular slot 14 and the semi-circular projection 15 in each tooth and the co-operating flange 4 on the end piece 2 are not centrally disposed of the length thereof, but 25 are formed more or less nearer one end than the other. Thus, there will be avoided the possibility of placing the individual teeth wrongly on the strip 1 and this will ensure 30 all the shoulders 17 on the teeth 12 facing in one direction so that all the teeth will be properly spaced.

The details of construction of the comb shown by Figures 7 to 12 inclusive are similar to those described above and need not 35 therefore be described at length herein as the only difference consists in that the teeth 12 have service points at one end only, the end pieces 2 and 7 being modified to correspond to the shape of the teeth so as to provide 40 a comb of a pleasing appearance.

The comb shown in Figures 13 to 19 is modified in that instead of the tooth locking member 6 being screw-threaded as above and adapted to be turned to lock the teeth 12, in 45 this case it is fixed to its end plate 7 and curved throughout its length as shown in Figure 19, and, being made of flexible metal or material, on being passed through the central passageway formed by the semi-circular recesses 16 formed in the teeth 12, the 50 said member 6 will be straightened and this will provide the necessary locking action.

Furthermore, the semi-circular depression 11 in the supporting strip 1 is dispensed 55 with and the locking member 6 is therefore also semi-circular or flattened on one side as it only has to fit the semi-circular recesses 16 in the teeth 12. On the other hand, the depression in the strip 1 can be retained and 60 the flange 15 and recess 16 in each tooth 12 dispensed with.

Figures 20 to 26 inclusive show a comb of identical construction to that shown in the figures just described with the exception 65 that it has service points on one side only;

a detailed description is therefore not necessary.

Referring now to Figures 27, 28 and 29, there is shown a device for holding spare teeth for the comb or for receiving the 70 teeth from the comb when it is desired to replace a broken tooth or to remove the teeth from the comb for cleansing or other purposes.

This device comprises an elongated body 75 portion 20 of the same cross section as the tooth supporting strip 1, that is to say it is rectangular in cross section and is provided with a semi-circular depression 21 in one face thereof if the comb with which it is to 80 co-operate has a similar depression.

One end of this device is formed with a head 22 which acts as a stop for the teeth 12 as will be realized by a consideration of Figure 29, whilst at the other end the body portion 85 is provided with an elongated circular rod 23.

When it is desired to use the device the end piece 7 and the locking member 6 are removed from the comb and the said rod 90 23 is then passed through the longitudinal passageway formed by the semi-circular depression 11 in the strip 1 and the co-operating recesses 16 in the teeth 12 when the latter can be readily slipped off the supporting 95 strip 1 on to the body 20 of the device.

What I claim and desire to secure by Letters Patent is:—

1. A comb of the class described, having, in combination, a tooth supporting strip, a series 100 of teeth arranged thereon and projecting therefrom, an end piece carried by the supporting strip at one end for holding the teeth in position in one direction, a second end piece, a locking member extending therefrom and adapted to engage the series of teeth and press them in the opposite direction and lock them on the supporting strip. 105

2. A comb of the class described, having, in combination, a tooth supporting strip, an 110 end piece fixed at one end thereof, a series of teeth arranged on the strip and projecting laterally therefrom, a second end piece, a locking rod carried thereby and extending laterally therefrom, and means whereby the 115 rod can be passed transversely through the bodies of the series of teeth to engage the first-mentioned end piece, thus locking the teeth on the strip between the two end pieces.

3. A comb of the class described, having, 120 in combination, a rectangular tooth supporting strip, an end piece fixed at one end thereof, a series of teeth having thereon openings to permit of their being threaded on to the strip, a second end piece, a circular locking 125 rod carried thereby and extending laterally therefrom, a semi-circular depression in one face of the strip and extending longitudinally thereof, complementary semi-circular recesses in the series of teeth forming a cir- 130

cular passageway, extending longitudinally of the comb and adapted to receive the locking rod to lock the teeth on the comb, and means in the first-mentioned end piece to receive and retain the end of the locking rod.

4. A comb of the class described, having, in combination, a tooth supporting strip having a semi-circular depression disposed in one face and running longitudinally thereof, an end piece fixed to one end of the strip, a series of teeth having therein openings to permit of their being threaded on to the strip, and, in addition, semi-circular recesses which form, with the depression in the strip, a circular passageway running longitudinally of the comb, a second end piece, a circular locking member rotatably mounted therein and extending laterally therefrom adapted to enter the longitudinal passageway formed in the teeth and supporting strip, a wheel mounted on one end of said locking member, a screw-thread on the opposite end of said member and a co-

operating threaded recess in the first-mentioned end piece to engage the screw-threaded end of the rod to lock the teeth on the supporting strip on the revolution of the wheel.

5. In a comb of the class described, a holding strip, sectional teeth having slots to correspond in contour to said holding strip and adapted to thread said teeth on said holding strip thereby, thinned end portions on said teeth, and a one sidedly raised central portion on said teeth, so as to insure the proper spacing of the thinned end portions of said teeth.

6. In a comb of the class described, having separate sectional teeth, a guiding slot in said teeth, said guiding slot being excentrically placed in said teeth, so as to insure the proper position for said teeth and signal their irregular placing when threaded on a center holding strip of said comb.

JULIUS DUNNER.
